PROTECTING AND LAUNCHING DEVICE FOR
LIFEBOATSThorolf Schröder-Nielsen, Oslo, Norway; vested
in the Alien Property CustodianApplication October 28, 1941, Serial No. 416,884
In Norway October 19, 1940

3 Claims. (Cl. 9—22)

The present invention relates to improvements in life boats, and particularly to means for strengthening and protecting of ships' life boats under all conditions. A main object of the invention is to reduce the difficulties arising in connection with launching during listing and rolling of the ship.

Proposed devices for overcoming these difficulties provide the side of the boat facing the ship with removable appliances sliding or rolling against the side of the ship. Such appliances have, however, the disadvantage, that the boat must be freed from them when coming to water, which is difficult especially under the adverse conditions under which they often must be used, and further, they offer only a temporary protection of doubtful value.

According to the present invention the boat on both sides of its center, preferably where the breadth of the boat differs only little from its largest breadth, is provided with a metal ring (or a ring of other suitable material) encircling the boat at right angles to its longitudinal axis and being formed with ring tracks permanently connected to the boat so that the rings may be considered as parts of the same.

The rings are preferably provided with rollers or the like between the fixed ring tracks and the freely rotatable outer ring member enabling the latter to roll against the ship's side with little friction during the lowering and hoisting of the boat.

The cooperating portions of the rings may have channel formed, T-formed, box formed or other suitable cross section and are placed on the boat at a suitable distance one from the other. The rotatable ring should not be too small but should have ample clearance for its movement. A construction wherein only two rollers or a limited number of rollers bear when the ring is under pressure is of advantage, as then a minor deformation of the ring will not cause serious trouble.

If the boat is not built in such a way, for instance provided with a double bottom, that the rings may be located in a recess around the boat so that they extend only partly beyond the outside of the boat, there should be arranged around the boat immediately forward and aft of the rings belts of wood, cork or the like with streamline shaped cross section, located inside of the outer periphery of the ring so as to reduce the water resistance of the ring during travel of the boat through the water. For protection and strengthening of the boat the device may

5 with advantage be used as support for the cover of the boat and for various appliances such as masts, etc. The arrangement is suitable for use in connection with all boats on board a ship, even if they are not exactly life boats.

10 Ships' davits of the usual kind are not necessary on board the ship. The boat should preferably be suspended in its usual tackles or wire to a point on board the ship which is fixed in relation to the ship or has a limited movement so that it during the lowering and hoisting of the boat along the ship's side always will be well inside of the point in the boat to which the suspending wire or tackle is fastened. The angle of 15 the suspending means thus will ensure that the boat is being kept against the ship's side with a certain force which limits the tendency of the boat to swing during rolling of the ship.

15 In order to secure easy launching of the boat 20 from the deck there may in known way be provided inclined planes for the rolling members.

25 If the height between the decks of the ship is sufficient for accommodation of boats of this kind, they may with advantage be placed on a lower deck, whereby the higher deck may serve for fastening of the block serving for carrying and launching the boat.

30 The drawing illustrates various embodiments of the invention.

35 Fig. 1 is a side view of a life boat equipped with my improved launching and protecting device, with parts broken away.

Fig. 2 is a horizontal detail section and Fig. 3 is a vertical cross-section, taken respectively on 40 the lines 2—2 and 3—3 of Fig. 1.

Fig. 4 is a diagrammatic view, showing in full lines the position assumed by the improved launching and protecting device while the boat rests upon a deck and in dotted lines positions 45 assumed by said device while the boat is being launched from the usual drop davits.

Fig. 5 is a diagrammatic view similar to Fig. 4, but with the boat suspended by wires from a fixed support on the deck and the protecting device 50 modified in shape.

Fig. 6 is a detail side elevation and

Fig. 7 is a plan view of a ring joint.

55 In the drawing, the ring 1 is provided with bolts 3 for journalling rollers 2 circumferentially spaced therearound.

The ring is preferably made in separate parts connected one with the other, and rotates around the boat in guide track 5 which in the embodiment shown consists of a ring with channel formed cross section encircling the boat and be-

ing connected to the same by means of plates 4. If the ring 1, as mentioned above, is made in a plurality of parts linked together, the guide track 5 need not be exactly circular. This embodiment is particularly suitable where the boat during the lowering and hoisting must pass open decks in the ship's side, as the ring can roll over such openings. The element 6 is a streamline shaped belt on one side of the track portion of the ring. Between the rings the boat is provided with a double bottom 7.

The boat 8 rests with its keel 9 and side keels 10 fixed to the guide track 5 against which it is also stayed at higher levels. The channeled guide track 5 is shown in the form of a closed ring, the sides of which form guides for the movable ring 1 and the bight portion of which serves as track for the rollers 2 mounted in the ring 1. The boat is suspended by means of tackles or wires 13 in both ends of the boat.

Fig. 5 shows a boat with the device according to the invention, suspended by wires 13a in the fixed point 11a in the support 12a mounted on the deck of the ship. The boat rests on pivoted chocks 20 on the deck. When the chocks are knocked down, the boat can by means of the wire 14 connected to the suspending wire 13a at its lower end be lowered until the wire 13a comes to a vertical position. At the continued lowering in the usual way by means of the wire 13a, the rings of the boat will roll on the inclined planes 16 and against the ship's side. As a further measure against swinging of the boat a wire 17 may in a known way be arranged vertically along the ship's side, and an auxiliary wire 18 be provided, which at its lower end is connected to the wire 13a and at its upper end to the interconnected blocks 19, one of which runs on the suspending wire 13a and the other on the wire 17, thus keeping these wires at a fixed distance one from the other.

In the embodiment shown in Fig. 4 the boat is suspended by means of a tackle to the top 11b of a usual drop davit 12b. 15 is a usual screw device for dropping of the davit. The movement of the davit is limited to the position shown in

dotted lines. The boat is lowered by slackening the tackle 13b and dropping of the davit, whereunder the protecting and launching device of the boat, as described here above will remain in contact with the inclined plane 16 or the ship's side. The tackle 21 is an auxiliary tackle which if desired may be used for further securing of the boat against swinging during rolling of the ship, co-operating with the vertical wire 17 in a manner similar that of the block 19 of Fig. 5. The launching and protecting device mounted on the boat is in this figure the same as in Figs. 1-3.

In Figs. 6 and 7 is shown a preferred method of simultaneously journalling rollers 2 and joining adjacent sections of the ring 1. By providing a plurality of ring sections linked together by bolts 3, the rotation of the rings is facilitated even though the tracks 5 are not circular or if portions of the ring have been bent or damaged to a slight extent during previous usage.

What I claim is:

1. A protecting and launching device for boats comprising a plurality of ring tracks permanently connected to the outer side of the boat and encircling the boat transversely of its longitudinal axis at spaced intervals where the diameter is only slightly less than the largest breadth, and a plurality of rings carrying spaced rollers bearing upon said tracks, said rings being freely rotatable about the boat and adapted to present a substantially smooth outer bearing surface at all times.

2. A protecting and launching device for boats as recited in claim 1 wherein the ring tracks are formed as outwardly-open channel members and the rings are formed as inwardly-open channel members of lesser width than said tracks and with side walls extending within the channels of said tracks.

3. A protecting and launching device for boats as recited in claim 1 wherein the ring tracks are formed as outwardly-open channel members and the rings are formed in journalled sections joined together by pins, which pins also serve as journals for said rollers.

THOROLF SCHRÖDER-NIELSEN.
